CLAIM

I claim the ornamental design for a multifunctional air fryer, as shown and described.

DESCRIPTION

FIG. 1 is a front perspective view of a multifunctional air fryer showing my new design;
FIG. 2 is a front view thereof;
FIG. 3 is a back view thereof;
FIG. 4 is a left-side view thereof;
FIG. 5 is a right-side view thereof;
FIG. 6 is a top view thereof;
FIG. 7 is a bottom view thereof; and,
FIG. 8 is a front perspective view in open position thereof. The broken lines in the drawings depict portions of the multifunctional air fryer that form no part of the claimed design.
